UNITED STATES PATENT OFFICE.

JOHN GAMGEE, OF LONDON, ENGLAND.

THERMO-DYNAMIC ENGINE.

SPECIFICATION forming part of Letters Patent No. 240,400, dated April 19, 1881.

Application filed February 26, 1881. (No model.)

To all whom it may concern:

Be it known that I, JOHN GAMGEE, of London, England, at present residing in the city of Washington, District of Columbia, have invented certain new and useful Improvements in Thermo-Dynamic Engines, or, more particularly stated, in the method of and apparatus for using a liquefiable gas or vapor at low temperature as a motor fluid, of which the following is a specification.

My invention relates to the employment, as a motor fluid, of a liquefiable gas or vapor of adequate tension, the product of a liquid which boils at or near the temperature of surrounding objects. I find that by working such a gas or vapor expansively in one or more engine-cylinders its heat can be converted to such an extent into mechanical energy or motion that at the exhaust it will have returned, in great measure, to its original liquid condition, from which state it may be again caused to assume the condition of a motor vapor or gas by exposing it to the needed temperature. It is this feature—viz, the working of such a vapor or gas expansively to the extent of more or less complete liquefaction and then reconverting it from the liquid to the vaporous or gaseous condition for use again as a motor fluid which mainly characterizes my invention.

The vapor having expended its energy and being mostly liquefied by the conversion of its heat into motion, is discharged from the engine-cylinder into a closed exhaust-vessel protected or insulated from environing heat. The maintenance of the exhaust at the boiling-point (for atmospheric pressure or thereabout) of the liquid used may be insured in various ways—for instance, by means of an injector or pump. By the injector or pump, or both, the cooled vapor is forced into an apparatus, for convenience' sake termed a "boiler," where it is exposed to the temperature needed to restore it to its original tension, and thence returns to the engine.

It will thus be seen that it is my object to obtain in a motor-engine the conditions of a closed circuit with a liquid boiling at a low temperature relatively to water transformed into vapor, the molecular energy of which is converted into the mass or molar motion of

the piston, so that its initial condition is restored. In this way, in a heat-engine, I extend the temperature within which the heat is utilized downward in the direction of the absolute zero, instead of upward above the temperature of surrounding objects. The intense heat of boiler-furnaces, the internal working-heat necessary to the formation of water-steam, the abundant exhaust waste of the steam-engine, difficulties of lubrication, &c., are one and all avoided by my invention.

The cycle I propose can be performed more or less satisfactorily with almost any liquid yielding expansive vapor below the temperature at which water boils; but in developing most power with most compact apparatus it is essential to use a compound which has a maximum amount of latent heat. The agent which I find in practice most available for this purpose is anhydrous ammonia, the boiling-point of which, at atmospheric pressure, approaches closely to 34.4° centigrade. At 0° centigrade its vapor tension is 3,183.34 millimeters, or about four atmospheres, while at 10° it attains to 4,574.03 millimeters, or six atmospheres. When the mean temperature attains 20° centigrade no less a pressure is exerted than 6,387.78 millimeters, or nine atmospheres; and at 30° centigrade, or tropical heat, it reaches over 8,000 millimeters, or over ten and one-half atmospheres in tension. Since at blood-heat two hundred pounds to the square inch is available, it is evident that the usual temperature of ocean or river water is most desirable in practice and best, in my opinion, when below 20° centigrade.

The latent heat of ammonia is about 900° as against 960° for water. It is this latent heat which I use in developing energy, so as to reduce the amount of rejected heat to a minimum and obtain a maximum rate of liquefaction. Although high pressures are attainable at low temperatures, it will always be found best in practice to work below rather than over one hundred pounds to the square inch.

From the fact that I utilize heat in this system downward to 0° centigrade and below toward absolute zero, I propose, for convenience, to name the apparatus which I employ "zeromotor."

In the accompanying drawings is represented

an apparatus adapted to carry into effect my invention. I wish it to be understood, however, that I do not restrict myself to the particular construction and combination of parts which compose the apparatus, for these may be varied to suit special conditions, so long as the apparatus as a whole is adapted to carry out the cycle of operations hereinbefore specified.

10 Figure 1 is a side elevation, partly in section. Fig. 2 is a plan of the apparatus. Fig. 3 is a section on line xx' , Fig. 1. Fig. 4 is a section on line yy' , Fig. 1. Fig. 5 is a view of a modification hereinafter referred to.

15 The engine shown in the drawings is a double-cylinder rotary engine, B being the first or high-pressure cylinder, and B' the second or low-pressure cylinder, into which the first cylinder exhausts through pipe d. As seen in 20 section, Fig. 3, the gas or vapor enters the cylinder B through the valve a and sliding division-port a', which runs in contact with the eccentric rotary piston C in the usual way. The admission-valve is operated from the rocking 25 valve-rod a² in the usual way, said rod having an arm, a², which bears against the rotating adjustable cut-off cam b, whose shaft b' is rotated through the medium of eccentrics and connecting-rods from the main shaft D in the 30 ordinary manner. The exhaust-port of the first cylinder is shown at d' in communication with the exhaust-pipe d, which leads to the gas or vapor admitting valve of the second cylinder, B'. The latter, with its accessories, is similar, 35 except in size, to the first cylinder, B, the shaft D being common to both, and the two cylinders are combined together for operation in the same way as the two cylinders of an ordinary compound or double-cylinder rotary engine.

40 The pipe e conducts the liquefiable gas or vapor to the primary cylinder B from the dome A^x of the part A, which, for convenience' sake, will be termed the "boiler," and which will be 45 hereinafter described.

45 The exhaust-pipe f from the second cylinder, B', leads into the closed exhaust-vessel E. This vessel receives, through the exhaust-pipe f, the liquefied vapor and gas from the second 50 cylinder.

55 From the upper part of the exhaust-vessel leads a pipe, g, to the larger cylinder, F, of a compound or double cylinder rotary pump, F F', driven by the rotary shaft D. The larger of these pump-cylinders is shown in section in Fig. 4. The smaller or high-pressure cylinder, F', with its accessories, is the counterpart of the other, and has its induction-port in communication with the eduction-port of the larger 60 cylinder through the intermediary of pipe h. The eduction-port of the smaller cylinder, F', communicates, through pipe h', with the space in boiler A, which receives the liquid from which the motor gas or vapor is to be generated. The pump being of known description, and the arrows in Fig. 4 indicating plainly the direction of motion and the induction and

eduction, further description of this instrumentality is unnecessary.

Boiler A is a metallic shell, containing at 70 each end an inner hollow head, A', and a space, i, between that head and the outer head, A, to receive the liquid—preferably water—which takes the place of fuel as a heater for the liquid ammonia. Pipes j lead from one space i 75 to the other, passing through without having communication with the hollow inner heads, A'. Into the space i on one side enters the water-induction pipe i', and from the opposite space i leads a water-eduction pipe, i². Water 80 entering through pipe i' will circulate through spaces i and pipes j, and will pass out through i². The interiors k of the hollow heads A' are in communication by means of pipes l, each of which surrounds concentrically one of the pipes j, and is sufficiently larger to leave between it and the pipe, i, an annular space, through which the ammonia can pass from one space k to the other. The water is permitted by proper means to circulate, not only through pipes j, 85 but also around the exterior of the ammonia-pipes z. Alternating partitions m are formed in the spaces k, so that the ammonia-vapor shall be caused to follow a tortuous path in passing through the pipes l and spaces k. 90

The eduction-pipe h' from the pump leads into the lower part of one of the spaces k, and through this pipe the pump discharges into the ammonia-space of the boiler A any ammonia vapor or gas that may be in the exhaust-vessel E. 95

From the bottom of the exhaust-vessel leads a pipe, n, which communicates with the lower part of the other one of the spaces k, and through this pipe is conducted from the exhaust into the 100 boiler the ammonia which has liquefied by reason of the conversion of its heat into mechanical energy. In order to force the liquid into the boiler I make use of an injector, (indicated at G,) using as motive power therein a jet of ammonia gas or vapor at high pressure, obtained from an auxiliary ammonia-boiler, H. This 105 boiler is supplied with ammonia by means of a small steam or other power-driven pump, I, which draws the supply of ammonia needed 110 from some suitable part of the apparatus—in this instance from the lower part of boiler A, through a pipe, o, and forces it into the auxiliary boiler through pipe o'. The boiler H is stayed by bolts or tie-rods p, to resist pressure, and 115 heat is supplied to the ammonia it contains by means of a system of piping, r s. Heated water, supplied from any suitable source, enters the space r' through pipes r', thence passes up through the pipes r, thence down through 120 the outer concentric pipes, s, which are closed at their upper ends, into space s', and out through pipe s². Ammonia-vapor at high 125 pressure can be thus generated, the vapor passing from the boiler to the injector through a pipe, t. In the pipe t, or upper part of the boiler, is a regulating or safety valve, t', which, when the pressure exceeds the prescribed limit, rises. In so doing it lifts a pivoted lever,

t^2 , attached to a connecting-rod, t^3 , which, at its lower end, is attached to the valve v , that regulates the flow of the incoming heating-water. In proportion as the safety or regulating valve t^4 rises the valve v closes, and I thus regulate the supply of heat to the boiler.

The apparatus is provided at all needed points with proper valves and cocks, and with check-valves to prevent back-pressure, as will be understood without further explanation.

The operation is as follows: The ammonia gas or vapor passes from the boiler into the smaller or high-pressure cylinder, where it is worked expansively, the cut-off being adjusted, for instance, to one-tenth of the stroke. In thus expanding and doing work the gas parts with its heat to a considerable extent. It thence exhausts into the second or lower pressure-cylinder, where it is cut off at, say, one-half the stroke, and is thus caused to do further work expansively. The result is that the vapor, by the time it passes from the second cylinder into the exhaust, has been almost entirely liquefied, only an exceedingly small proportion of the ammonia retaining vaporous form. The engine thus may be said to act not only as a motor, but as the condenser. From the exhaust-vessel the ammonia is, by means of the compound pump and injector, forced back into the boiler to be again brought to the condition of a motor gas or vapor.

In Fig. 5 is represented, in further illustration of my invention, a plan of an apparatus in which a compound reciprocating engine and compound reciprocating pump are employed instead of the rotary engine and pump. In this apparatus the high and low pressure cylinders are horizontal, and in each cylinder the exhaust on each side of the reciprocating piston leads from the lowest part or bottom of the cylinder, so that the liquefied ammonia can be conducted off without difficulty. The lettered parts in this figure indicate parts which correspond in function to like lettered parts in the preceding figures. The compound engine and pump require no detailed description, being constructed and arranged in a manner similar to compound reciprocating steam engines and pumps which have heretofore been used.

In order to keep the pump-cylinders cool they are preferably surrounded by a water-jacket, as indicated at F^2 , Fig. 4. The cooling liquid enters at w , and is discharged at one or the other of the openings w' .

In order to shield the exhaust-vessel from the heat of surrounding objects, I inclose it in a metallic tank, J . The confined air within vessel J forms a good non-conductor of heat.

It will be found desirable in many cases to have one or more vessels accessory to the exhaust-vessel, in which a vacuum may be maintained or absorbents held for the purpose of relieving the exhaust-vessel or of emptying any part of the machine, as circumstances may require. Such a vessel, which may be called an "absorber," is shown in Fig. 1, at K , placed in the same tank J which contains the exhaust-

vessel. It is constructed for the most part like a tubular boiler, the tubes y being intended for the circulation of warm water or other heating medium. A pipe, z , leading from the ammonia-space of the boiler or exhaust or other suitable part of the apparatus enters the vessel, and is perforated, as shown at z' , to permit ammonia to pass therefrom into the vessel, which is to be filled with some absorbent of ammonia. This vessel is intended to serve as a place where the ammonia can be stored temporarily when access is to be had to any part of the interior of the apparatus.

By properly regulating the cocks and valves with which the apparatus is provided the ammonia can be diverted into this vessel, where it will be taken up and held by the absorbent. Whenever it is desired to withdraw the ammonia therefrom warm water or other heating medium is caused to circulate through the tubes or heating-space of the vessel. This causes the vaporization of the ammonia, and said vapor is carried off by the pump through the valve or cock-controlled pipe z^2 , which communicates at one end with the upper part of the vessel K and at the other end with the pipe g .

I remark that, in lieu of the injector a force-pump, such as pump I , can be used to force liquid directly from the exhaust into the boiler. In fact, there are various means by which the equilibrium may be permanently disturbed, so that the exhaust may, during the operation of the engine, discharge into the boiler.

Having described my invention, what I claim, and desire to secure by Letters Patent, is—

1. The method of condensing a liquefiable gas or vapor (the product of a liquid of low boiling-point) used as a motor-fluid in a thermo-dynamic engine, which consists in working said gas or vapor expansively to the extent of more or less complete liquefaction in giving motion to the engine, substantially as hereinbefore set forth.

2. The method herein described of using a liquefiable gas or vapor (the product of a liquid of low boiling-point) as a motor-fluid for engines, which consists in working said vapor or gas in the engine expansively to the extent of more or less complete liquefaction, then exhausting the vapor thus liquefied into a suitable receiver, thence conveying it to a boiler where it is subjected to the low degree of heat needed to bring it again to the condition of a motor gas or vapor, and thence returning it to the engine to again go through the same cycle of operations, substantially as hereinbefore set forth.

3. The combination of an engine proper, in which a liquefiable gas or vapor is worked expansively to the extent of liquefaction, so that said engine shall serve not only as motor, but as condenser, a closed exhaust-vessel which receives the liquefied gas or vapor from the engine-cylinder, a boiler, and means, substantially as described, for forcing the contents of

said exhaust-vessel directly to the boiler, the combination being and acting substantially as hereinbefore set forth.

4. In a thermo-dynamic engine, in which a liquefiable gas is used as the motor-fluid, substantially as specified, the combination, with the engine-cylinder, of a closed liquefied gas-receiver or exhaust-vessel protected by a non-conducting covering from the heat of the environment.

5. In a thermo-dynamic engine, vessels accessory to the exhaust-vessel in which a vacu-

um may be maintained or absorbents held for the purpose of relieving the exhaust-vessel at any moment, or emptying any part of the machine, as circumstances may demand, substantially as set forth.

In testimony whereof I have hereunto set my hand this 25th day of February A. D. 1881.

JOHN GAMGEE.
